INVENTOR.

UNITED STATES PATENT OFFICE.

JOSEPH SAVOIE, OF CENTRAL FALLS, RHODE ISLAND, ASSIGNOR OF ONE-HALF TO EDWARD C. GLINES, OF PROVIDENCE, RHODE ISLAND.

BOTTLE.

SPECIFICATION forming part of Letters Patent No. 726,992, dated May 5, 1903.

Application filed January 8, 1903. Serial No. 138,222. (No model.)

To all whom it may concern:

Be it known that I, JOSEPH SAVOIE, a citizen of the United States of America, and a resident of Central Falls, Providence county, Rhode Island, have invented certain new and useful Improvements in Bottles, of which the following is a specification.

My invention relates to improvements in bottles in which a controlling-valve stem extends downward through the interior of the bottle and is operated upon the outside of the bottle at the bottom thereof; and the purpose of my improvement is to provide a bottle which admits of easy filling the first time, but which cannot be refilled thereafter without destroying certain essential and material parts of my improvement. I attain this object by the device shown in the accompanying drawings, in which—

Figure 1 is a vertical section through the central line of the bottle; Figs. 2 and 3, details of the valve-case, and Figs. 4 and 5 the controlling mechanism at the bottom of the bottle.

The same parts are designated by the same letters throughout the several views.

In Fig. 1, A represents the body of the bottle, partially filled with liquid *l*. A' is the mouth of the bottle, and A³ the bottom part, hollowed sufficiently to make room for the controlling mechanism. Within the neck of the bottle, *c* represents a tightly-fitting cylinder of cork or other suitable material, pierced for the accommodation of the cylinder *d*, which fits tightly into *c*. The cylinder *d* is flanged at the top, the flange being represented by *d'*. The upper part of the mouth of the bottle is of larger bore than the lower part, forming the shelf *b'*, on which the flange *d'* rests, the upper surface or edge of the cork *c* coming flush with this shelf *b'*. A plan view of this flange is shown in Fig. 3, and, as seen in that figure, the flange is perforated with the holes *d²* *d²*. Immediately above the flange *d'* is situated the cylinder *e*. This cylinder is provided with projecting lugs *e²* *e²*, (seen best in Fig. 2,) corresponding in number and form to the perforations *d²* *d²* in said flange. These lugs are inserted through the perforations *d²* and bent under the flange *d'*, so as to secure the cylinder *e* to said flange. This

method of uniting the said flange and cylinder, however, is not material to my invention, as any other equivalent mechanical process will answer equally well. The cylinder *e* is of such a size as to leave an annular seat upon said flange *d'* for the valve *f*, which is made, preferably, of rubber. *f* is centrally perforated for the valve-stem *i*, which runs through the entire length of the bottle and on which *f* fits loosely. Above the valve *f* is the washer *g*, and washer and valve are retained in position by the nut *h* and the threaded upper extremity of the valve-stem *i*. The cylinder *e* contains a plurality of perforations *e' e'*, as shown in Fig. 2. The number of these holes is immaterial, so long as they are sufficient to discharge the contents of the bottle.

Outside of the cylinder *e* is the cap *j*, of such a size as to leave a space between itself and the cylinder *e* for the contents of the bottle to pass through. The upper part of the cap *j* is perforated with a plurality of holes *j'* for the egress of the liquid. Outside of the inner cap *j* is an outer cap *k*, which fits closely over the inner cap *j* in such a manner that after the cap *j* is placed in position the outer cap *k* can be thrust down between *j* and the neck of the bottle by a moderate application of force. Within the neck of the bottle is the indentation *b²*, passing entirely around the interior of the neck. The outer cap *k* has at two or more points in its inclosing wall and at a suitable distance from the lower edge of *k* the catches *k²*, stamped outwardly from the body of *k*. The parts *e* and *k* are made of some suitable non-corrosive metal, and the structure of the catches *k²* is such that when the cap *k* is thrust into the space between the bottle-neck and the inner cap *j* the catches *k²* are sprung inwardly until the indentation *b²* is reached, when they spring outwardly into said indentation, retaining the outer cap *k* securely in place, so that the same cannot be removed.

The inner cap *j* is made, preferably, of glass, although it may also be made of a suitable metal.

The valve *f* is operated by the valve-stem *i* and the mechanism shown in detail in Figs. 4 and 5.

The bottom of the bottle is perforated, as

shown, with a hole a little larger than i , so as to admit of the flanged packing nn' , made, preferably, of rubber, and serving to make a tight joint between the stem i and the bottom 5 of the bottle. The lower end of i is much enlarged, as shown at i' , and this enlargement is threaded and provided with a thumb-nut $m m'$.

o is a metallic washer, through which i 10 freely passes, and serves to retain the packing n in place and also to form a bearing for the spiral spring p , placed between o and i' and surrounding the stem i . This stem is recessed for a short distance at its lower end, 15 (shown by i^2) the enlargement i' , however, closing the recess at the bottom. Communicating with the recess i^2 are the two holes i^3 and i^4 , bored through the shell of the recess, as shown in Figs. 4 and 5.

20 There is also a hole m^2 bored through the wall or shell of the thumb-nut $m' m$.

My device operates as follows: The stem i is inserted through the packing n and thence upward to the bottle-neck, the thumb-screw 25 $m m'$ being in the position shown in Fig. 4, the hole i being stopped by the rubber packing n . The bottle is now filled in the usual way. After filling, the cork c , with the tube d and cylinder e , is inserted in the bottle- 30 neck and the valve f slipped upon the upper end of i and secured in place by its washer and nut $g h$. Over these is placed the inner cap j and then the outer cap k , and the bottle is complete. To draw off the contents of the 35 bottle, the thumb-nut $m m'$ is unscrewed, so as to take the position shown in Fig. 5. A slight pressure of the thumb upon $m m'$ forces the stem i upward, thus freeing the valve f and allowing the contents to escape through 40 the perforations in e and k , while air is admitted to the bottle through the holes i^3 and i^4 , the latter being now beyond or farther into the bottle than the packing n . When $m m'$ is not unscrewed quite so far as shown in Fig. 45 5, air is admitted through the hole m^2 in the side of the thumb-nut and thence through i^3 and i^4 into the bottle interior.

It will be seen that the perforations in j are not in the central portion, but close to the 50 rounding wall of the outer cap k , while those in k are in the center thereof. Being thus out of line prevents the insertion of a wire or other instrument, and thus insures the valve f from being tampered with.

When the bottle is emptied, no more liquid 55 can be introduced, as the slightest pressure of liquid through the caps $j k$ forces the valve f down upon its seat regardless of the position of the stem i .

Having now described my invention, what 60 I claim, and desire to secure by Letters Patent, is—

1. A bottle having an orifice in the bottom thereof; a valve seated in the neck of the bottle; a seat adapted to receive said valve; a 65 valve-stem actuating said valve and normally retaining the same against its seat and extending downwardly through the interior of the bottle and thence out through said orifice in the bottom thereof, and means for operating said valve-stem, substantially as set forth.

2. In a bottle a valve seated in the neck of the bottle, a valve-stem extending downwardly through the bottom of the bottle; said 75 stem having at its lower end the recess i^2 and the holes i^3 and i^4 communicating therewith, and the enlarged threaded head i' ; in combination with a thumb-screw $m m'$ and a spiral spring p operating to keep said valve normally closed, substantially as described.

3. In a bottle the combination of a valve seated in the neck of the bottle; a valve-stem sliding loosely through said valve; a washer and nut upon said stem above said valve and 85 controlling the operation of the same; an orifice in the bottom of said bottle for the passage of said stem; and means for operating said stem and admitting air through the same into the bottle, substantially as described. 90

4. In a bottle the combination of a valve seated in the neck of the bottle; means for operating the same; a perforated cylinder enclosing said valve; a perforated cap j surrounding said cylinder so as to leave a space 95 between them; an outer cap k having a plurality of catches k^2 and an indentation b^2 around the inside of the bottle-neck adapted to hold said catches and lock the cap k in position, substantially as set forth.

Signed at Pawtucket this 30th day of December, 1902.

JOSEPH X SAVOIE.
